UNITED STATES PATENT OFFICE.

CHRISTIAN H. MARTIN, OF SIOUX CITY, IOWA.

GRAND-PIANO TRUCK.

SPECIFICATION forming part of Letters Patent No. 402,340, dated April 30, 1889.

Application filed December 29, 1888. Serial No. 294,983. (No model.)

To all whom it may concern:

Be it known that I, CHRISTIAN H. MARTIN, a citizen of the United States of America, residing at Sioux City, in the county of Woodbury and State of Iowa, have invented certain new and useful Improvements in Grand-Piano Trucks, of which the following is a specification, reference being had therein to the accompanying drawings.

10 This invention has relation to improvements in piano-trucks for convenience and facility in handling or moving pianos; and to these ends the nature of the invention consists of the combination of parts, including 15 their construction, substantially as herein-after fully set forth and claimed.

In the accompanying drawings, Figure 1 is a perspective of my improved piano-truck, showing it as applied in one form for use. 20 Figs. 2 and 3 are a plan and a side view of the same, respectively; and Figs. 4 and 5 are detail views thereof.

In the embodiment of my invention I provide a skid, A, the forward end of which is 25 provided with eyes or ears a a, or other suitable means for the application of the draft thereto. The skid is provided near its forward end with a cushioned support, b, while at its opposite end it is provided with a cushioned back, b', and a push hand-rod, a', as 30 also with a cushioned support, b'. The skid is also provided with elevated cushioned supports B B, one of which is arranged near each support b b'. Each support B consists of a 35 frame, B', the upper cross-bar of which is upholstered or plush-covered, while its lower cross-piece consists of a plate, B³, which fits under a keeper or cleat, d, fastened to the skid A.

40 The plush-covered or upholstered cross-bars of the cushion-frames B' B' are provided at their ends with short plates or cheek-pieces d' d'. These stand upright or vertically when said frames are in their folded position or 45 lying flat upon the skid to receive between them the piano disposed sidewise thereon, as is practiced in moving pianos with the same. The frames B' B' or cushions proper are held in their upright positions by means of braces 50 or plates B³ B³, hinged or articulated to the upright or vertical bars of the frames and to the short plates e e, fastened to the skid A.

The hinging or articulating of the braces or plates B³ B³ permits of the folding of the frame B' flat down upon the skid A, as seen in a 55 number of the figures. To the sides of the skid A, intermediately of the elevated cushions B B, are secured keepers or staples f, into which may be inserted standards, or through which may be passed straps or other 60 means for steadyng or binding the piano to the skid.

C C are trucks or rollers borne by axles C' C', which are carried by bails C² C², hung, preferably, between the skid and the supports or cushions b and b', or other convenient points upon the skid.

It will be seen that in moving a piano, for instance, the skid, with the supports B B in their elevated position, is run under the piano and the rear legs removed, letting the piano rest thereon. The supports are then lowered, permitting the piano at that edge to descend with them, the piano then being stood side- 70 wise upon the supports. The other legs of 75 the piano, if not already removed, are now taken off. The trucks or rollers having previously been disposed, as shown in a number of the figures, with their axles resting under the skid, the transportation of the piano can 80 now be readily effected with convenience and facility by the application of the draft at the forward end, aided by pushing the same from the rear or at the side or from both the rear and side. In passing down a flight of steps 85 or a stairway the trucks or rollers are swung so as to remove their axles from under the skid, permitting the skid to rest and slide directly upon the steps. Upon reaching the foot of the steps or a level, the rollers or trucks, 90 it is obvious, can be readily returned to their former position and again serve as a means for bearing the skid; also, upon reaching the point or place of destination, the legs of the upper or elevated side of the piano are again 95 put in position and that edge lowered, permitting the inserted legs to rest upon the floor. The opposite edge or side of the piano is now raised by returning the supports B B to their elevated position, when the other legs 100 can be put in place and the skid removed and disposed out of the way, ready for future use.

Buttons or pivoted plates g g are applied to the skid A at its ends, which are adapted to

take or rest under the axles C' of the rollers or trucks C, and retain the rollers or trucks elevated when necessary—as, for instance, in descending steps or a stairway, as above set forth.

Having thus described my invention, I claim—

1. The skid provided with rollers carried by axles borne by bails, said skid having buttons or pivoted plates engaging with said axles, holding said rollers elevated, substantially as and for the purpose set forth.
2. The skid provided with elevated rests or supports, each consisting of a frame, with its lower cross piece or plate engaging with a cleat or keeper fastened to the skid, the upper side of the said frames having braces or props hinged or articulated to the skid and frames, substantially as and for the purpose specified.
3. The skid provided near its front and rear ends with cushioned supports, as also a cushioned back at its rear end, and with elevated folding cushioned supports or rests, substantially as and for the purpose set forth.

4. The piano-moving truck consisting of 25 the skid provided with eyes or ears for the application of the draft thereto, and with a cushioned back having a hand push-rod connected therewith, the elevated folding cushioned supports having their braces hinged 30 thereto and to the skid, the lower cross bars or plates thereof engaging with keepers or cleats applied to the upper side of the skid, and trucks or rollers hung upon said skid, and pivoted buttons or plates to engage with 35 the axles of said rollers, holding the latter elevated, said skid also having fixed cushioned supports secured thereto, substantially as and for the purpose indicated.

In testimony whereof I affix my signature in 40 presence of two witnesses.

C. H. MARTIN.
